UNITED STATES PATENT OFFICE.

HENRY C. WILLIAMSON AND HERMAN PRIES, OF MICHIGAN CITY,
INDIANA.

UNDERFRAMING FOR CARS.

SPECIFICATION forming part of Letters Patent No. 774,222, dated November 8, 1904.

Application filed July 5, 1904. Serial No. 215,346. (No model.)

To all whom it may concern:

Be it known that we, HENRY C. WILLIAMSON and HERMAN PRIES, citizens of the United States, and residents of Michigan City, county 5 of LaPorte, and State of Indiana, have invented certain new and useful Improvements in Underframing for Cars, of which the following is a specification and which are illustrated in the accompanying drawings, forming a part 10 thereof.

This invention relates to car construction, and has particular reference to certain improvements in underframes of that character employed with box-cars, although it is not 15 restricted in its use to cars of this especial class.

The objects of the invention are to generally improve the substructure or underframe of railway-cars, and particularly with reference to the central sills and the manner of mounting the bolsters, as well as to provide a strong and rigid chair or support carried by the central sills for supporting the end sills and dead-wood of the car-body.

25 The invention consists of the construction and arrangement of parts hereinafter particularly described, and designated in the appended claims and illustrated in the accompanying drawings, in which—

30 Figure 1 is a longitudinal section of the underframe of a car constructed in accordance with our invention and partially broken away between the ends to facilitate illustration. Fig. 2 is a section on the line 2 2 of Fig. 1, the sides of the frame being broken away. Fig. 3 is a section on the line 3 3 of Fig. 1. Fig. 4 is an end elevation of the frame, and Fig. 5 is a perspective of one of the chairs designed to be secured to the central sills and employed to support the end sills and dead-wood.

40 In carrying out our invention we make the central sills in sections, such sections terminating at sufficient distances apart to permit 45 of locating the bolsters between the adjacent ends of such sections, and tie these ends together in such manner as to secure the rigidity and strength of continuous sills and avoid-

ing the necessity of cutting through the sills to provide for the reception of the bolsters 50 when made of continuous lengths or of forming the bolsters of two sections and riveting the sections to the sills.

Preferably each sill is made of three sections, such as the end sections 10 and an intermediate section 11. As shown in Fig. 1, the adjacent ends of the three sections terminate sufficiently far apart to receive between them the bolsters 12, and the two central sills are also spaced apart any suitable distance to 60 receive between them the draw-bars. (Not shown.)

The sill-sections 10 and 11 are preferably made of channel-shaped steel beams, having their flanges extending outwardly, as shown 65 in Fig. 3, and are tied together in such manner as to render the sills exceedingly rigid and strong. To this end we employ metal angle-bars 13, which bridge the space between the ends of the sections 10 and 11 and are riveted to such sections. As shown in Figs. 1 and 2, the angle-bar associated with each sill is located on the outer face of such sill and is disposed with one of its leaves vertical, while the other leaf extends outwardly from the 75 sill at the lower edge of the vertical leaf, suitable means, such as rivets 14, securing the sill-sections and angle-bars 13 together.

The vertical leaves of the angle-bar 13 are relatively narrow, and as these bars are located near the upper edge of the channel-beams forming the sills a suitable space under the bridging angle-bars and between the ends of the sill-sections is provided for the reception of the bolsters. We also employ, 85 in addition to the angle-bars 13, metal reinforcing-plates 15, located on the opposite sides of the sills from the angle-bars 13 and also secured by the rivets 14. A spacing ring or washer 16, located between the vertical leaf 90 of the angle-bar 13 and the plate 15 and secured by a rivet 17, serves to eliminate vibration at this point and strengthen the parts.

To impart greater rigidity to the sills, an upper tie-plate 18 is employed and secured, 95 as by rivets 19, to the upper flanges of the ad-

jacent ends of the sections 10 of both sills and of the adjacent ends of both sections 11 of the sills, thus bridging the bolster-space.

The bolster 12, which may be of any suitable construction, but which is preferably made wholly of metal and of the character shown, extends between the ends of the sill-sections. In the construction illustrated each bolster consists of a pair of substantially Z-shaped side plates or bars so disposed that the upper flanges 20 thereof extend outwardly, while the lower flanges 21 extend inwardly, the web 22 being vertical.

Located on each upper flange and extending longitudinally thereof is a plate 23, the inner edge of which projects beyond the edge of the web 22. A cap-plate 24 connects the upper flanges 20, the parts being secured in assembled relation by means of rivets 25 passing through the horizontal flange of the angle-bar 13, the cap-plate 24, plates 23, and the flanges 20 of the Z-beams. Suitable bolts 26 passing through the horizontal flanges of the angle-bars 13, the cap-plate 24, and the projecting edges of the plates 22, furnish additional securing means, bolts being here preferably employed in lieu of rivets, owing to the inaccessible location of the projecting edges of the plates 22.

The inwardly-extending flanges 21 of the Z-bars are secured together by a bottom plate 27, riveted thereto and extending the length of the bolster. The bolster is secured at its bottom to each sill by a cross-plate 28, the ends of which are riveted, as at 29, to the lower flanges of the channel-beams of the sills, while rivets 30, countersunk in the plate 28, pass therethrough and secure the bolster thereto, as shown, the center bearing-plate 31 being riveted to the bottom tie-plate 28.

L-shaped angle-bars 32, riveted to the inner faces of the vertical web of the channel-beams 10 and 11 and to the bottom tie-plate 28, are provided and located at opposite sides of the bolster, so as to abut against the latter, as shown in Fig. 1, thereby giving greater strength and rigidity to the structure and effectually bracing the bolster.

By means of the construction and arrangement of the parts described we provide an organization in which the center sills possess all the advantages of continuous sills, including rigidity and strength, and which obviates the objections to the continuous sill in the manner of mounting and securing the bolster. Moreover, the sills may be made of shorter-length steel beams and are therefore cheaper of manufacture than the continuous-length sills.

Rigidly secured to the outer end of each sill—that is to say, the outer end of each beam 10—is a chair designed to support and have secured thereon the end sills and dead-wood of the car structure. Each of these chairs (designated generally as 33) is preferably, though

not necessarily, made of cast metal and consists of a horizontal channel-shaped base 34, having its web vertical and its flanges extending outwardly, as shown in Fig. 4, its lower flange 35 being disposed in extension of the lower flange of the adjacent end sill-section 10, while its upper flange 36 is disposed in a plane below the upper flange of the end sill-section and terminates in a vertical flange 37, extending above the upper flange of the end sill-section. The flange 37 is provided with a lug 38, riveted to the adjacent end of the upper flange of the sill-section 10.

Each chair 33 is provided with a rearward extension or web 39, which is offset, as shown in Fig. 2, to receive the vertical web of the end sill-section 10, the inner face of the latter being flush with the inner face of the web of the base 34, as shown in Fig. 2. The web 39 is riveted to the web of the sill end section 10, and the lug or cheek plates 40 of the draft-rigging are secured upon the inner faces of sill end sections and the webs of the bases 34 of the chairs. The horizontal and vertical flanges 36 and 37 of each chair provide an L-shaped seat whereupon rests the wood end beam 41, which is secured to such flanges by bolts 42, as shown in Fig. 1, while the dead-wood beam 43 rests upon the outer ends of the chair-seats and is secured in position by bolts 44, passing therethrough and through the horizontal flanges 36 of the chair-base 34.

The nailing-strips 45, to which the flooring is nailed, are secured upon the upper flanges of the central-sill beam-sections, as shown in Fig. 3, and the draw-bar hanger or strip is secured to the beam 43 in any suitable manner, as by means of the bolts 44 and additional end bolts 46 passing through the dead-wood.

We claim as our invention—

1. In a metallic car-underframe, the combination with the central sills, each of which consists of a plurality of sections, bolsters extending between the adjacent ends of the sections, and tie-plates above and below the bolster and overlapping the adjacent ends of the sill-sections and secured thereto.

2. In a metallic car-underframe, the combination with the central sills, each of which consists of a plurality of channel-beam sections, bolsters extending between the adjacent ends of the sections, L-shaped bars for connecting the sill-sections and to which the bolsters are secured at the top, and a plate secured to the adjacent ends of the sections of the sills at the bottom and upon which the bolster rests and is secured.

3. In a metallic car-underframe, the combination with the central sills, each of which consists of three sections, a bolster extending between the intermediate and each end section, L-shaped bars having their vertical flanges secured to the adjacent ends of the sill-sec-

tions and their horizontal flanges secured to the top of the bolster, a plate secured to the adjacent ends of the sections of both sills upon which the bolster rests and is secured, and L-shaped bars secured to the sill-sections and the said plate and abutting against the bolster.

4. An end-sill chair comprising an angle-plate forming a seat for the bottom and rear face of an end sill, a horizontal flange extending backwardly from such plate to engage the top of a center sill, and a vertical flange extending backwardly from the vertical member of such plate and downwardly from its horizontal member and having a lateral flange at its lower edge.

5. In a metallic car-underframe, the combination with the central sills composed of chan-

nel-beams having the flanges thereof extending horizontally, of an end-sill chair associated with the end of each central sill and comprising a channel-iron base provided with a horizontal flange in a lower plane than the upper flange of the central sill and a vertical flange extending above the upper flange of the central sill, a lug on the vertical flange secured to the upper flange of the central sill, and a plate projecting from the base and secured to the web of the central sill.
